UNITED STATES PATENT OFFICE.

DANIEL WALKER WILSON, OF NEW BEDFORD, MASSACHUSETTS.

SPARKING PLUG.

No. 834,179.

Specification of Letters Patent.

Patented Oct. 23, 1906.

Application filed February 16, 1904. Serial No. 193,837.

To all whom it may concern:

Be it known that I, DANIEL WALKER WILSON, a citizen of the United States, residing at New Bedford, in the county of Bristol and 5 State of Massachusetts, have invented new and useful Improvements in Sparking Plugs, of which the following is a specification.

This invention relates to certain new and useful improvements in sparking plugs used 10 primarily in gas or gasoline engine cylinders, and is of the type wherein a succession of sparks are formed at the inner end of the plug to make the ignition of the gases more certain to create explosions.

15 The object of the invention is to provide in a spark-plug an electrode extending from a core of insulation to coöperate with a second electrode extending from the said core, said two electrodes being in line with a third electrode, all of said electrodes being arranged in series in the circuit whereby to form a succession of jump-sparks.

Many other objects and advantages will be 20 hereinafter referred to and be particularly 25 pointed out in the claims.

In the drawings, Figure 1 is a vertical section of my improved sparking plug applied to a cylinder. Fig. 2 is a perspective view of the same looking from the inside.

30 1 represents a cylinder; 2, the piston; 3, my improved spark.

The plug consists of a casing 4, of any preferred pattern and construction, formed at its inner end with threads 5, which engage 35 threads 6 in the end of the cylinder 1. A shoulder 7 is formed in the casing 4, and at the outer end of the latter it is enlarged and threaded, as at 8, to receive the threaded portion 9 of a nut 10. A core 11, of any insulating material, is fitted in the casing 4, and it is 40 formed with flanges 12 and 13 and a central opening 14. The core is placed in the casing, flange 12 abutting against the shoulder 7. The nut 10 is screwed into place and abuts 45 against the flange 13, thus rigidly holding the core within the casing. A spindle 14 is passed through the opening 14 and is firmly held in position by the threads 16 and a finger-nut 18. On the inner end of the spindle is formed 50 a tip or electrode 19, of platinum or German silver or other suitable material.

Embedded in the inner end of the core 10 is an electrode 20, (for the purpose of clearness to be hereinafter termed the "first" electrode,) its free end being located adjacent to and slightly spaced from the tip 19. A sec-

ond electrode 21 is embedded in the end of the casing 4, and its inner end is located adjacent to and spaced from the first electrode, as will be readily understood by reference to the 60 drawings.

The arrangement of the means for making and breaking the circuit in the operation of the piston is illustrated conventionally in Fig. 1, wherein 21 is the spindle-contact; 22, 65 the casing-contact; 23, the circuit-wires; 24, the battery; 25, the cam operated by the piston, and 26 the brush to contact with the cam and close the circuit.

As the piston reciprocates the circuit is 70 opened and closed, causing a spark to jump from the electrode 19 to the front electrode 20, thence to the second electrode 21, creating two sparks, as will be well understood, the current passing through the spindle and electrodes, as indicated by the arrows. The making of two jump-sparks in such quick succession within the cylinder is accomplished so rapidly that it creates practically an elongated flame, which makes the ignition more 75 positive, in that it ignites a greater volume of gas.

80 In practice I have found that by placing the gaps at the end of the plug the value of the spark is materially increased. Furthermore, it is essential that the gaps be made in 85 series in the circuit to cause the current to jump across the space between the electrodes to produce the succession of sparks.

I do not desire to be limited to a construction capable of forming two sparks, as it is 90 evident that the number of gaps may be multiplied; hence the number of sparks increased, as may be desired.

What I claim as new is—

95 1. A sparking plug consisting of a casing, a core of insulation therein, an electrode projecting from the core, a second electrode projecting from the core adjacent the first electrode, and an electrode secured in the casing adjacent the other electrodes, all of said electrodes being arranged in series in the circuit.

2. A sparking plug comprising a casing, a core of insulation therein, a spindle passing through the core, an electrode projecting from the spindle, an electrode secured to the core adjacent the spindle-electrode, and an electrode projecting from the casing adjacent both the other electrodes, all of said electrodes being arranged in series in the circuit. 105

3. In a sparking plug, the combination of 110 a shell adapted to be secured to the combus-

tion-cylinder of an engine, an insulating-tube secured to said shell, said tube provided with a cap and binding-post, a bar or wire located through the insulating-tube and extending 5 beyond the inner end of the insulating-tube, a metal point extended from the shell and an intermediate metal point secured to the insulating-tube and the points spaced from each other and in series in the circuit, substantially

10 as and for the purpose specified.

4. A spark-plug adapted to be secured in the cylinder of an explosion-engine and having an inwardly-projecting finger constituting one terminal of an electrical circuit, an 15 insulated conductor in such plug the inner end of which constitutes another terminal which is adjacent to but separated from the first, and a conductor or metal piece fixedly attached to the insulation and interposed between such terminals or in such position as to 20 cause the current to pass therethrough.

5. A spark-plug adapted to be secured in

the cylinder of an explosion-engine, having an insulated conductor the inner end of which constitutes a terminal for an electrical 25 circuit, and a metal piece attached to the insulation and projecting adjacent to such terminal and adapted to divide the space between said terminal and the other terminal for such circuit in the cylinder into distinct 30 gaps.

6. A sparking plug carrying at one end a plurality of electrodes arranged in one line and in series in the circuit and sufficiently closely related to form a linear succession of 35 jump-sparks in touch with one another.

In testimony whereof I have signed my name to this specification in the presence of two subscribing witnesses.

DANIEL WALKER WILSON.
